DESCRIPTION

FIG. 1 is a perspective view of a mobile computing device docking station, showing a first embodiment of our new design;

FIG. 2 is a right side view of the first embodiment, a left side view thereof being a mirror image;

FIG. 3 is a top view of the first embodiment;

FIG. 4 is a front view of the first embodiment;

FIG. 5 is a rear view of the first embodiment;

FIG. 6 is a bottom view of the first embodiment;

FIG. 7 is a perspective view of a mobile computing device docking station, showing a second embodiment of our new design;

FIG. 8 is a right side view of the second embodiment, a left side view thereof being a mirror image;

FIG. 9 is a top view of the second embodiment;

FIG. 10 is a front view of the second embodiment;

FIG. 11 is a rear view of the second embodiment; and,

FIG. 12 is a bottom view of the second embodiment.

Broken line areas in the figures form no part of the claimed design and are for illustrative purposes only. The different shading patterns shown in FIGS. 7–12 represent a darker and lighter tone of gray.
